DISPENSING CABINET FOR SPHERICAL OBJECTS

Charles A. Cowser, Miamisburg, Ohio

Application April 16, 1954, Serial No. 30,047

Term of patent 14 years

(Cl. D52—2)

Figure 1 is a perspective view of a dispensing cabinet for spherical objects, showing my new design and Figure 2 is a top plan view thereof.

The spherical objects shown in broken lines represent fishing bobbers or the like, and are shown for illustrative purposes only.

I claim:

The ornamental design for a dispensing cabinet for spherical objects, as shown and described.
